UNITED STATES PATENT OFFICE

PAUL A. NEMOEDE, OF CHICAGO, ILLINOIS, ASSIGNOR, BY MESNE ASSIGNMENTS, TO CONTAINER CORPORATION OF AMERICA, OF CHICAGO, ILLINOIS, A CORPORATION OF DELAWARE

SHIPPING AND DISPLAY BOX

Application filed May 9, 1928. Serial No. 278,362.

My invention relates to packing, shipping and display boxes and has to do particularly with cardboard, or similar, boxes of this character.

5 One of the objects of my invention is to provide a novel means for securely fastening the box walls in their box-closing position and which is of such character that the walls may be easily and quickly unfastened and moved 10 to an open position without injuring the walls or other parts of the box.

Another object is to effect the detachable fastening of one wall to another wall by applying at intervals to either of the surfaces 15 to be attached a substance which will repel glue, or other adhesive substance, leaving raw adhesive spaces between the repelling spaces whereby when the glue, or other adhesive substance, is applied to either or both of the surfaces 20 faces to be attached such surfaces will be fastened together only at spaced intervals. This arrangement, while securely fastening the walls in closed position, permits them to be readily unfastened by passing an object between the attached wall surfaces successively 25 breaking the connected spots apart. In carrying out the foregoing object, any composition having an oil base and which may be applied to the box surface, such as printer's 30 ink, paraffin, etc., may well serve as the repelling substance. Consequently, my invention may be well adapted to paraffin-treated boxes; boxes having advertising matter printed upon its outer surface; and where a colored background surface is applied to the 35 box.

A further object is to provide a simple and inexpensive manner of spot-fastening a box wall in its closing position upon the box. 40 Other objects and advantages will become apparent as this description progresses and by reference to the drawings wherein,—

Figure 1 is a perspective view, partially in section, of a box embodying my invention, the 45 top wall being shown in its box-closed position;

Fig. 2 is a bottom plan view of a blank from which the box of Fig. 1 may be formed.

With particular reference to the form of 50 box shown in the drawing, it may be formed

of cardboard, or other similar material, from a single blank cut and creased along fold lines as shown in Fig. 2. More specifically, this particular box blank comprises a box bottom portion 10 having end walls 11, rear wall 12 and front wall 13 connected thereto along the respective fold lines 11', 12', and 13'. The front and rear walls are each provided at their opposite ends with flaps 14 and 15, respectively. All of these walls and flaps are 55 adapted to be folded to the positions clearly indicated in Fig. 1 to receive and confine the articles to be shipped and/or displayed. It will be noted that in this particular form of box, the end walls 11 are tapered toward the 60 front wall 13, the purpose being to more fully and clearly expose the articles packed therein when the box is opened.

The box structure above described is provided with an integral top structure comprising the top-covering surface 16 connected to the rear wall 12 along the fold line 16'. This portion 16 is provided with end flaps 17 and 18 and a front-fastening flap 19 which are 65 adapted to be folded to the position indicated in Fig. 1. It will be noted that the top portion 16 and the end flaps 17 and 18 are provided with fold lines 20 and 21 joined by a central cut line 22 which provides an arrangement for folding that portion and its end flaps together about the fold lines 20 and 21 70 with the central cut portion 16a thereof projecting vertically above the box. This is such a position as the top covering wall 16 75 may assume when the box is used for display purposes; and, in that event, the detached front cover flap 19 may be disposed at the rear of the box between the inner surface of the rear wall and the articles in the box for holding the cover in that position, as will be well 80 understood.

In boxes of this character which are used for both shipping and display purposes, it is very important in some instances that the top wall be tightly fastened upon the box 85 during shipment and that the form of connection be such that it may be readily and quickly broken without injuring the box and destroying its usefulness for display purposes. The important feature of my in- 90 100

vention is the provision for the foregoing desirable arrangement. More specifically, an adhesive-repelling substance is applied at intervals to the surface of the top wall flap 19 along its outer edge, this surface being that which is adapted to lie next to the inner surface of the box front wall 13 when this wall flap is attached thereto. Such repelling substance is indicated at 23 in the drawing. 5 Raw, untreated and adhesive spaces 24 are thus provided at intervals to provide a spot-fastening means. The repelling substance may take various forms. I have found that printer's ink, paraffin, or other substances 10 having an oil base, serve this purpose exceedingly well. In some instances spirit varnish may be used. It is well known that various forms of boxes used for shipping and packing purposes are subjected to paraffin 15 treatment and in boxes of that kind, the paraffin treatment may be readily omitted at intervals along the surface of the cover which is to be attached. For example, in the form of box shown in the drawing, the paraffin 20 may be omitted at the points indicated by the numeral 24, namely, at the spots between repelling surfaces 23. Also, there are many 25 forms of boxes having advertising matter printed on the outer surface thereof in which cases the printing ink may serve as the repelling substance, it being applied at the 30 places indicated at 23 in the drawing. In some cases the entire box surface is colored by applying ink thereto, and in such cases, 35 the ink may be omitted at intervals along the surface of the wall to be attached, as in the case of the paraffin, so that blank, raw, untreated surfaces, such as indicated at 24 in the drawing, are provided. Although I have 40 shown and described the adhesive-repelling substance as applied to the top wall flap, it is to be understood that it may also be applied to the surface of the other box wall to which the flap, or other part, is to be fastened without departing from my invention. 45

In further carrying out my invention, the glue or other suitable adhesive material, is preferably applied continuously along the surface which has been treated with the adhesive-repelling substance and in the form 50 shown this adhesive material is applied to the portion of the top wall flap indicated generally at 19^a (Fig. 2). In view of the fact that the treated spaces 23 on the cover 55 flap repel the glue substance, no adherence will take place at those points, the adherence being only at the raw, untreated spots or spaces 24 between the spaces 23. Thus, when the box blank is set up or partially set up 60 and the top wall to be attached is moved to its attachment position against the other wall surface, with the glue, or other similar substance, applied as above described, the top wall flap 19 will be secured to the inner surface of the front wall 13 only at the inter- 65

vals indicated by the raw, untreated spaces 24 thereby providing a spot-glue fastening arrangement. While this arrangement is such as to securely fasten these parts together against separation under normal conditions, it will be appreciated that they may be readily separated by passing an object along the glued surfaces between the front wall 13 and the flap 19 so as to successively break the fastened spots loose. It is to be understood 70 that while I preferably apply the glue, or other adhesive substance to the treated surface of the flap, it may be applied instead to the inner surface of the box wall engaged by the flap. 75

To readily permit of the insertion of one's finger or other object between the box front wall and the cover front flap as above stated, the central portion of the flap 19 is cut away as at 25 in Fig. 2. The adjacent portion of the front wall is extended upwardly as at 26 to conceal the opening 25 in the flap without interfering with the insertion of an object through said opening. To break the fastened surfaces apart, an object may be 80 inserted between the box front wall lip 26 and the flap 19 and into the flap opening 25 and it may be then moved laterally along the spot-glued surface to free the top wall as above mentioned. This not only permits 85 this wall to be loosened very readily and quickly, but it also avoids injuring of any of the exposed surfaces of the box whereby, when the box is opened, it may then be used 90 for display purposes as above set forth. 95

It will be appreciated that while I have chosen one particular form of box for illustrating my invention, it may well be adapted to many other forms of boxes where similar results are desired. My invention may be employed for joining any two of the walls together regardless whether such walls have fastening flaps. The walls may be joined together before the blank is entirely set up in which case the box may be filled by inserting the articles therein through one of the ends as is done at times in the use of a box such as that shown. My invention is equally well adapted for closing a box of any form having a cover or other wall which is to be fastened in its closed position after the articles have been packed therein. Furthermore, while I have shown a certain relationship between the adhesive and non-adhesive surfaces, yet such relation and the arrangement of such surfaces may be varied without departing from the spirit and scope of my invention as defined by the claims which follow. 110

I claim:

1. In a paper box, a covering part supported by one wall surface, an extension carried by said part adapted to be attached to another wall surface, said extension having a portion intermediate its ends cut away, a 120

- glue-repelling substance applied at intervals to the surface of said extension at the opposite sides of said cut away portion and a glue substance applied continuously along said same surface whereby said extension will adhere to said attachment-wall surface at spaced points only, said cut away part also preventing adherence of the extension with the adjacent wall surface and providing for insertion of an object between said extension and wall surface for breaking the adhering surfaces apart, said attachment wall having an extended part concealing said cut-away portion in said extension.
2. In a paper carton, a plurality of side walls, a cover supported by the upper edge of one of said side walls, a flap on the edge of said cover opposite its supported edge, said flap having a central cut-out, spot-adhesive-fastening means on said flap on the opposite sides of said cut-out for fastening the cover to another of said side walls, said latter side wall having an edge extension opposite said cut-out for concealing the latter and for leaving a slit between the flap and latter side wall for the insertion and lateral movement of an object along the spot-adhesive-fastening means to open the cover.
3. In a paper carton, a plurality of side walls, a cover supported by the upper edge of one of said side walls, a flap on the edge of said cover opposite its supported edge, said flap having a central cut-out, an adhesive-repelling substance applied at intervals along the free edge of said flap on the opposite sides only of said cut-out and an adhesive substance applied along said flap over said adhesive-repelling substance for fastening the cover to another of said side walls, said latter side wall having an edge extension opposite said cut-out for concealing the latter in the closed position of the cover and for leaving a slit between the flap and latter side wall for the insertion and lateral movement of an object along the flap-fastened surface to open the cover.
4. In a blank for a paper carton, a single piece of material creased to provide sections which when folded constitute a plurality of walls and flaps, the outer of which are a fastening flap and a side wall, said flap section having a central cut-out, adhesive-repelling means disposed at intervals along the free edge surface of said flap on the opposite sides of said cut-out, an adhesive substance applied along and over said last-mentioned flap surface, and an extension on said side wall which in the folded and closed position of said box overlies said cut-out to conceal the same and to leave a free space between said flap and side wall for the unobstructed insertion of an object to detach said flap from said side wall when it is desired to open the carton.
5. In a paper box, a wall swingably sup-
- porting another wall, a third wall to which said second wall is to be fastened in overlapping relation, and means for fastening said walls together and permitting detachment of the same without injury thereto, said means including an adhesive-repelling agent applied at intervals along the edge surface of one of said walls, and an adhesive substance applied along said same surface and rendered non-adhesive at intervals by said agent, the exposed edge portion of the outer overlapping wall section being thus wholly unsecured to the adjacent wall section between at least certain of the portions of the wall sections on which the adhesive is effective whereby the insertion of an object to detach the wall sections from each other is facilitated.
6. In a paper box, a cover wall having a free edge surface when said cover is unattached, another wall surface to which said edge surface on said cover wall is glued to hold the cover wall in its closed position, the portion of said cover wall edge surface to be attached to said latter wall surface having an adhesive resisting substance applied thereto along spaced areas and also having adhesive applied thereto over an area overlapping and intermediate said glue resisting areas whereby said adhesive causes adherence only over spaced areas between the adhesive resisting areas, the free edge of said latter wall surface being entirely unsecured to said cover wall edge surface at least along portions thereof adjacent said adhesive resisting areas whereby separation of said wall surfaces is facilitated.
7. In a paper box, wall sections providing overlapping edge portions adapted to be glued together, the edge portion on one of said wall sections having an adhesive resisting substance applied thereto along spaced areas and also having adhesive applied thereto over an area overlapping and intermediate said glue resisting areas whereby said adhesive causes adherence between said overlapping edge portions only over spaced areas between the adhesive resisting areas, that overlapping edge portion presenting an exposed free edge being entirely unsecured to the adjacent overlapping edge portion at least along portions thereof adjacent said adhesive resisting areas whereby separation of said wall sections is facilitated.
- In testimony whereof, I have subscribed my name.
- PAUL A. NEMOEDE.
